UNITED STATES PATENT OFFICE.

JOHN ANDREW ORMISTON, OF CALGARY, ALBERTA, CANADA, ASSIGNOR OF THIRTY-THREE AND ONE-THIRD ONE-HUNDREDTHS TO JEREMIAH WILFRED HEFFERNAN, OF EDMONTON, ALBERTA, CANADA.

HEAD-LAMP ADJUSTER.

1,304,505.

Specification of Letters Patent. Patented May 20, 1919.

Application filed March 5, 1918. Serial No. 220,535.

To all whom it may concern:

Be it known that I, JOHN ANDREW ORMISTON, a subject of the King of Great Britain, residing at Calgary, in the Province of Alberta and Dominion of Canada, have invented new and useful Improvements in Head-Lamp Adjusters, of which the following is a specification.

This invention relates to head lamp adjusters, the object in view being to produce a simple device which may be applied to any ordinary head lamp for use on an automobile, motor truck, locomotive, street car, or other vehicle, the main object being to prevent blinding rays of light from being thrown from a head lamp in such manner as to interfere with the drivers of other machines or pedestrians, and traffic in general, the device being designed to comply with the traffic regulations which, in some localities, require that the rays of light from a head lamp must not be elevated more than twenty-four inches above the ground at a distance of seventy or eighty feet in front 25 of the vehicle carrying the lamp.

A further object of the invention is to increase the efficiency of the lamps and the illuminating properties thereof by concentrating the rays of light upon the road for 30 a considerable distance in front of the vehicle.

A further object of the invention is to so construct and arrange the elements of the invention as to not interfere with the vision 35 of the driver and occupants of the vehicle upon which the lamp is carried.

With the above and other objects in view, the invention consists in the novel construction, combination, and arrangement of 40 parts, as herein described, illustrated and claimed.

In the accompanying drawing,

Figure 1 is a front elevation of a head lamp equipped with this invention.

Fig. 2 is a vertical diametrical section through the same.

The improved device comprises a screen A of opaque material, preferably metal, the said shade slightly exceeding one-half of a 50 disk and having a slightly arched bottom edge, as shown, the highest point of the arch being below the center of the bulb L of the lamp, as shown in the drawing. In addition to the screen A, the device comprises

an inclined reflector C which is of inverted 55 dish shape, the front edge thereof being arched as indicated by dotted lines in Fig. 1, and the rear edge thereof being arched to a greater degree and lying in contact with the forward face of the reflector 60 H of the lamp as shown in Fig. 2. The forward edge of the reflector C lies in contact with or in close proximity to the screen A and is fixedly secured to said screen, forming a fixed part of the attachment. Pins 65 G extending backwardly from the screen A serve to hold the whole device in place in the lamp and prevent the turning of said screen and the reflector C carried thereby, the main reflector H of the lamp being 70 formed with holes in which said pins G are inserted.

Secured to the rear face of the screen A is a license number holding frame B comprising the flanges or lips D which are disposed 75 radially with respect to the center of the lamp as indicated in Fig. 1. An arcuate license number plate E is inserted in the plate holder and is formed of translucent material, such as opaque, or frosted, or 80 ground glass, the numbers on the plate E being visible through an opening E' of corresponding shape formed in the screen A.

The reflector C has its lower face nickel plated or otherwise highly polished, so as to 85 deflect the rays of light from the bulb L downwardly, thus preventing the elevation of the rays of light from the lamp. Said reflector C is formed with perforations or openings F, so as to provide for the necessary illumination of the interior of the body of the lamp above said reflector C in order to correspondingly illuminate the number plate E. The body of the lamp is represented at I and the front thereof is 90 covered with the usual glass or lens K.

From the foregoing description, taken in connection with the accompanying drawing, it will now be understood that the combined screen and reflector will so condense or deflect the rays of light from the bulb that no blinding rays of light are transmitted which will interfere with the operators of other vehicles and traffic in general, and the illumination will be confined to the road 100 way in front of the vehicle. At the same time, the operator and occupants of the vehicle on which the lamp is mounted will

have perfect vision as to the general traffic. Furthermore, the license number of the vehicle will be clearly displayed by night, as well as by day.

5 I claim:—

1. The combination with a head lamp, of an opaque screen substantially in the form of one-half of a disk arranged directly behind the front glass or lens of the lamp and 10 extending below the center of the light bulb, an inverted dish shaped reflector carried by and extending rearwardly from said screen over the light bulb and having its rear edge in contact with the main reflector of the 15 lamp, said screen being formed with a display opening above the main opening, said dished reflector being formed with light transmission openings to provide for the illumination of that portion of the screen 20 having the display opening.

2. The combination with a head lamp, of an opaque screen substantially in the form of one-half of a disk arranged directly behind the front glass or lens of the lamp and extending below the center of the light bulb, 25 an inverted dish shaped reflector carried by and extending rearwardly from said screen, said reflector extending from the screen rearwardly over the light bulb and having its rear edge in contact with the main reflector 30 of the lamp, said screen being formed with an arcuate display opening, a translucent number bearing plate arranged behind said opening, and plate holding means on the back of said screen, said dished reflector 35 being formed with openings to provide for the illumination of said number plate.

In testimony whereof I affix my signature.

JOHN ANDREW ORMISTON.
